[57] **CLAIM**

The ornamental design for a wave-shaped scanner, as shown and described.

DESCRIPTION

FIG. 1 is a top view of the wave-shaped scanner;
FIG. 2 is a bottom view of the wave-shaped scanner;
FIG. 3 is a front elevational view of the wave-shaped scanner;
FIG. 4 is a rear elevational view of the wave-shaped scanner;
FIG. 5 is a left-side elevational view of the wave-shaped scanner;
FIG. 6 is a right-side elevational view of the wave-shaped scanner;
FIG. 7 is a perspective view of the wave-shaped scanner;
FIG. 8 is a perspective view of the wave-shaped scanner when a cover is opened in half way; and,
FIG. 9 is a perspective view of the wave-shaped scanner when the cover is fully opened.
FIGS. 7-9 are drawn on a reduced scale.
